Primary Examiner — Susan Bennett Hattan*Assistant Examiner* — Brett Miller(74) *Attorney, Agent, or Firm* — Birch, Stewart, Kolash & Birch, LLP(57) **CLAIM**

The ornamental design for a medicine bottle lid display, as shown and described.

DESCRIPTION

FIG. 1 is a left side elevation view of a medicine bottle lid display;

FIG. 2 is a right side elevation thereof;

FIG. 3 is a front elevation view thereof, the rear view being a mirror image; and,

FIG. 4 is a top plan view thereof.

The bottom of the medicine bottle and medicine bottle lid to which the display is attached are partially shown in broken lines for illustrative purposes only and forms no part of the claimed design.

1 Claim, 4 Drawing Sheets**FIG. 2**

FIG. 4
